PROCESS OF SEPARATING MIXED MATERIALS

Walter L. Remick, Hazleton, Pa., assignor to Hydrotator Company, Cleveland, Ohio, a corporation of Delaware

Application June 19, 1931, Serial No. 545,510

8 Claims. (CL 209—173)

My invention consists in a new and useful improvement in process of separating mixed materials, and is designed for separating materials of different specific gravity, and more particularly for separating coal from slate or other non-combustible materials with which the coal is mixed, and also for separating ore from the various substances with which it is mixed. My invention involves the use of hydraulic classification in which the two materials of different specific gravity become separated in a fluid medium, and the particularly novel and valuable feature of my invention is the control of the density of this classifying fluid medium whereby the separation of the materials is facilitated.

While I have hereinafter fully described my improved process and one specific embodiment of apparatus for practicing my process as fully illustrated in the drawings filed herewith, it is to be distinctly understood that I do not consider my invention limited to this specific embodiment and its operation, but refer for the scope of my invention of both process and apparatus to the claims appended hereto.

In the drawings:

Fig. 1 is a side elevation of my apparatus.
 Fig. 2 is a top plan view of my apparatus.
 Fig. 3 is a vertical section on line 3—3 of Fig. 2. My improved apparatus may be suitably mounted in a frame-work formed of U-beams having the base of side beams 1 and end beams 2, the uprights 3, the top side beams 4 and cross braces 5. Suitably mounted on uprights 3 about midway between the side beams 1 and 4 are the beams 6 to which are attached the beams 7 on which is mounted the tank 8 having the overflow launder 9 with the discharge opening 10. Suitably positioned above the tank 8, I provide any suitable form of support 11 for the rotatable shaft 12 upon the lower end of which and suitably disposed in the tank 8 is the five-way pipe joint 13 carrying four distributing pipes 14 having thereon depending nozzles 15 disposed at an angle to the bottom 16 of the tank 8. The lower end of the joint 13 has the depending pipe 17 engaged over the upper end of the inlet pipe 18 extending upwardly through the bottom 16 of the tank 8. To this pipe 18 there is connected the discharge side of the pump P and I provide a check valve, as at C, between the pump P and the inlet pipe 18 so arranged as to permit flow of liquid from the pump P to the interior of the tank 8 and prevent escape of liquid from the tank 8 through the pipe 18 when the pump P is not in operation. I provide any suitable means for driving the pump P,

as a motor M. I provide a sump S mounted upon cross-beams 19 on the beams 1, and connected with the intake side of the pump P by the pipe 20. I provide a hopper H suitably supported by the uprights 3 with a discharge opening 21 communicating with the sump S. It is to be noted that the sump S has an inclined baffle plate 22, the lower edge 23 of which is spaced a short distance from the discharge opening to the pipe 20 at the bottom of the sump S, and its upper edge 10 24 spaced a short distance below the discharge opening 21 of the hopper H. I provide an overflow opening 25 for the sump S.

I provide an inclined shaker screen 26 suitably supported above the hopper H and below the discharge opening 10 of the tank 8, by flexible straps 27 attached to the beams 4. A shaft 28 mounted in journals 29 on the end uprights 3 has the eccentric shaker rod 30 attached to the screen 26. A pulley 31 is provided on the shaft 28 driven by 20 the belt 32 from the motor M—1 mounted on the beams 33 on the top side beams 4.

Suitably disposed adjacent the bottom 16 of the tank 8, I provide a discharge chute 34 leading from the interior of the tank 8 to the bottom of 25 the scraper elevator 35, and having the slide valve 36 with the control lever 37. I provide a motor M—2 on a bracket 38 on one of the uprights 3 for driving the elevator 35 by the belt 39 on the pulley 40 of the shaft 41 of the elevator 35. The elevator 35 is provided at its upper discharge 30 end with the chute 42 so disposed as to discharge on the screen 26. I provide on the screen 26 a dividing partition 43 to maintain separation of material discharged on the screen 26 from the discharge opening 10 of the tank 8, and material 35 discharged on the screen 26 from the chute 42 of the elevator 35.

From the foregoing description of the details of construction of my improved apparatus, its 40 operation in the practice of my improved process will be obvious. The sump S being filled with water by any suitable means of supply, the pump P fills the tank 8, the supply of water being made sufficient to completely fill both the sump S and 45 the tank 8. Thereafter, the continued operation of the pump P will cause the water to overflow the tank 8 from the discharge 10 of the launder 9 and pass through the screen 26 and hopper H to return to the sump S. It is to be noted that the 50 baffle plate 22 prevents the water, pouring down into the sump S from the hopper H, from entering directly into the pipe 20 to the pump P. This is done to prevent any air bubbles, caused by the fall of the water from the hopper H, from entering 55

the pump P. The water flowing over the upper end 24 of the baffle 22 then flows downwardly to the pipe 20 to the pump P.

The mixed materials, as for instance, coal and slate are fed into the open top of the tank 8 by any suitable means. By hydraulic classification and particles of the material of lesser specific gravity, coal, are carried upwardly by the flowing current of water and overflow on to the screen 26, while the particles of the material of greater specific gravity, slate, sink to the bottom 16 of the tank 8.

It is to be noted that the mixed materials are run into the tank 8 with a certain amount of additional water, which additional water escapes from the overflow 25 of the sump S.

When the coal particles are received upon the screen 26, those of a sufficiently large size as to be desirable are retained by the screen 26 and by its shaking action are caused to pass over and off of the screen 26 to be stored by any suitable means. The coal undersize particles pass with the water through the screen 26 and hopper H into the sump S, and a certain proportion of these coal particles escape from the sump S with the overflow water at 25.

When a sufficient quantity of slate particles has become deposited on the bottom 16 of the tank 8, the slide valve 36 is opened, allowing the slate to pass through the chute 34 into the elevator 35 by which it is raised to the chute 42 through which it is conveyed to the screen 26. By the action of the screen 26, the large particles of slate are disposed of, and the slate undersize particles pass with the water through the screen 26 and hopper H into the sump S and are therefrom returned to the fluid classifying medium in the tank 8.

It is obvious that in discharging both the coal and slate on the screen 26, I return both coal and slate undersize particles with the circulating water. Thus I use higher gravity material for building up the density of the fluid medium, which is a distinct advantage. In actual operation, I have proven that after operating for a while the proportion of heavy undersize in circulation increases with resultant improvement in the gravity separation. The overflow in the sump S of the undersize coal particles accounts for the gradual increase in the proportion of heavy undersize which does not overflow the sump S as freely as the undersize coal.

It is to be noted that variation in the size of the openings in the screen 26 through which the water must pass in returning to the sump S has a decided influence on the operation of my improved process. It controls the size and quantity of solid material returning to the classifying tank with the circulating water. This variation in the size and quantity affects the density of the classifying medium. This density factor constitutes the control of the gravity separation.

Having described my invention, what I claim is:

1. The process of separating mixed materials which consists in subjecting them to the classifying effect of an upwardly flowing current of a fluid medium; treating the mass of overflowed particles to segregate therefrom a definite proportion, of said mass, composed of particles having a definite size range; and introducing such proportionate mass into said fluid medium.

2. The process of separating mixed materials

which consists in subjecting them to the classifying effect of an upwardly flowing current of a fluid medium; treating the mass of settled particles to segregate therefrom a definite proportion, of said mass, composed of particles having a definite size range; and introducing such proportionate mass into said fluid medium.

3. The process of separating mixed materials which consists in subjecting them to the classifying effect of an upwardly flowing current of a fluid medium; treating the mass of overflowed particles to segregate therefrom a definite proportion, of said mass, composed of particles having a definite size range; introducing such proportionate mass into said fluid medium; treating the mass of settled particles to segregate therefrom a definite proportion, of said mass, composed of particles having a definite size range; and introducing such proportionate mass into said fluid medium.

4. The process of separating mixed materials which consists in subjecting them to the classifying effect of an upwardly flowing current of a fluid medium; treating the mass of overflowed particles to segregate therefrom a definite proportion, of said mass, composed of particles having a definite size range, subjecting such proportionate mass to the classifying effect of a second upwardly flowing current of a fluid medium, whereby a portion of said proportionate mass is overflowed; and introducing the remainder of such proportionate mass into said first current.

5. The process of separating coal from its associated refuse which consists in subjecting the mixed coal and refuse to the classifying effect of an upwardly flowing current of water; treating the mass of overflowed coal to separate therefrom a definite proportion thereof comprising coal particles having a definite size range; and introducing said coal particles into the current of water.

6. The process of separating coal from its associated refuse which consists in subjecting the mixed coal and refuse to the classifying effect of an upwardly flowing current of water; treating the mass of settled refuse to separate therefrom a definite proportion thereof comprising refuse particles having a definite size range; and introducing said refuse particles into the current of water.

7. The process of separating coal from its associated refuse which consists in subjecting the mixed coal and refuse to the classifying effect of an upwardly flowing current of water; treating the mass of overflowed coal to separate therefrom a definite proportion thereof comprising coal particles having a definite size range; introducing said coal particles into the current of water; treating the settled mass of refuse to separate therefrom a definite proportion thereof comprising refuse particles having a definite size range; and introducing said refuse particles into the current of water.

8. The process of separating coal from its associated refuse which consists in subjecting the mixed coal and refuse to the classifying effect of an upwardly flowing current of water; separating from the overflowed coal, and from the settled refuse, a determined proportion of each; commingling such separated portions in a determined ratio; and introducing said commingled mass into said current of water.

WALTER L. REMICK.
